UNITED STATES PATENT OFFICE.

ALFRED LAURAIN, OF PARIS, FRANCE, ASSIGNOR TO SOCIÉTÉ DU CAOUTCHOUC MANUFACTURÉ, OF PARIS, FRANCE.

ELASTIC WOVEN FABRIC AND METHOD OF WEAVING IT.

Application filed August 19, 1921. Serial No. 493,649.

(GRANTED UNDER THE PROVISIONS OF THE ACT OF MARCH 3, 1921, 41 STAT. L., 1313.)

To all whom it may concern:

Be it known that I, ALFRED LAURAIN, a citizen of the French Republic, residing at 86 to 90 Rue Notre Dame de Nazareth, city of Paris, France, have invented new and useful Improvements in Elastic Woven Fabrics and Methods of Weaving Them (for which I filed an application in France, dated September 8, 1913, Patent No. 473,146, and in Great Britain, dated July 5, 1920, Patent No. 146,468), of which the following is a specification.

This invention has reference to improvements in elastic woven fabrics, ribbons or bands and in the methods used for weaving them.

The main object of this invention is to produce an elastic fabric, ribbon or band which is more pliant and more supple and possess other important advantages as compared with such fabrics as heretofore made.

An important use to which this improved fabric, ribbon or band may be put is to be made up into braces, garters, hose supports, body belts and similar articles in which event this invention will obviate serious defects inherent in such articles when made from fabric as heretofore woven in that the latter exert a pressure on the whole surface over which they are stretched and further there is very little or no ventilation of that part of the body on which the article is being worn.

This invention consists in an elastic fabric, ribbon or band that is formed with transverse parallel ribs or ridges which project on both sides of the fabric, ribbon or band, the said ribs or ridges being arranged in series spaced apart so as to leave short lengths of fabric between them, which latter may be plain ribbed or brocaded. The series of ribs or ridges may be spaced apart at regular or irregular intervals.

The parallel transverse ribs referred to which stand out in relief on the two faces of the plain ribbed or brocaded fabric, ribbon or band form transverse channels between them for the circulation of air and they alone form the contacting surfaces with the body.

Such a band of more or less elastic fabric is rendered very pliable or supple longitudinally by reason of the ribs or ridges and in

a measure forms a pliant ventilated cushion which will not irritate the skin and has, therefore, a great advantage from the hygienic point of view.

The accompanying drawing represents the ordinary appearance of the extra supple new textile and the designing, enabling any specialist to mount and manufacture a type of this textile article.

Fig. 1 represents a plan view and the corresponding edge view of a piece of ribbon of this new tissue; *a* indicates the part in plain ribbed or brocaded elastic tissue and *b* the extra supple part with transverse ribs or ridges *c* which project on both sides. The parts *a* and *b* may be of variable lengths.

Fig. 2 is a plan view of the threading; 1 is the elastic rubber thread; 2, 3, 4, 5 are the ordinary non-elastic threads of the ground.

Figs. 3 and 4 represent a designing which comprises: a first piece, Fig. 3, showing the production of the plain ribbed or brocaded part *a* in one or several colours which may be in any required design and a second piece, Fig. 4, showing the production of the extra supple part *b* provided on its two faces with rectilinear parallel transverse ribs or ridges.

In Fig. 3, the designing of the first piece only represents four throws or passages of the weft, that is to say, the round, but it is understood that these four throws can be repeated as often as required, according as more or less great length is to be given to the part *a* of the tissue.

In Fig. 4 the designing of the second piece comprises two parts A and B which here each represent eight throws or passages of the weft; however, it must be clearly understood that each part may comprise a multiple of four when greater length is required in the part *b* of the extra supple tissue.

Fig. 5 is a diagram showing a weave.

To make this textile, there must be five comber boards 1, 2, 3, 4, 5 (Figs. 3 and 4). The squares in which two diagonal lines are traced and the squares covered with lines parallel to two sides represent the lifted or raised threads; the plain squares or those without hatching correspond to the depressed threads. The squares with diagonal lines represent the rubber threads.

The first piece, Fig. 3, is made as follows:—

At the first throw of weft, the warp threads corresponding with the comber boards 3 and 4 lift, whilst 1, 2, 5 descend.

At the second throw, the warp threads corresponding with the comber boards 1, 3, 5 lift, whilst 2 and 4 descend.

At the third, boards 2 and 5 lift and 1, 3 and 4 descend.

At the fourth, boards 1, 2, 4 lift and 3, 5 descend.

The fifth throw of weft is identical with the first, the sixth with the second, and so on.

To make parts A and B of the second piece, Fig. 4, the operation is as follows:—

For part A:—

At the first throw of weft, the warp threads corresponding with comber boards 3 and 5 lift, whereas 1, 2, 4 descend.

At the second throw of weft, the warp threads corresponding with comber boards 1, 3, 5 lift whereas 2, 4 descend.

At the third throw, boards 2, 4 lift and 1, 3, 5 descend.

At the fourth throw, boards 1, 2, 4 lift and 3, 5 descend.

The fifth throw is identical with the first; the sixth with the second; the seventh with the third and the eighth with the fourth.

These four throws of weft can be repeated as often as required.

For part B:—

At the ninth throw of weft which corresponds to the first throw of piece B, the warp thread corresponding to board 5 lifts whereas the warp threads corresponding to boards 1, 2, 3, 4 descend.

At the tenth throw, boards 1, 2, 4, 5 lift whereas 3 descends.

At the eleventh throw, board 4 lifts whereas 1, 2, 3, 5 descend.

At the twelfth throw, boards 1, 3, 4, 5 lift whereas 2 descends.

The thirteenth throw causes the same movements as the ninth, and so on, to the sixteenth throw. There will be only a sufficient number of throws to form a rib. Thereafter A is again repeated and then B, for the required number of ribs.

The designs are only effected by the warp.

From the foregoing, it is to be understood that those of the warp threads constituting the transverse ribs or ridges of the fabric do not involve rubber threads, the latter being only in the middle part of the thickness of the fabric. Therefore, these rubber threads are not so liable to be attacked by perspiration or friction against the human body, firstly, because they are supported some little distance above the surface of the body and, secondly, because of the ventilation that can take place, as described.

The warp and weft threads—other than the rubber threads—may be of any suitable textile thread, such as cotton, silk, artificial silk, ramie and the like.

What I claim and desire to secure by Letters Patent is:—

1. An elastic fabric presenting longitudinally on both faces a sequence of plain sections and of transversely ribbed sections, such plain sections being composed of interwoven rubber warp threads, textile warp threads and textile weft threads and said transversely ribbed sections being composed of a series of parallel ribs spaced apart at regular intervals and protruding above and under the fabric with respect to said plain sections, each of such ribs comprising textile warp-threads and textile weft threads, said rubber warp threads being bound in each rib neither with the said textile warp threads nor with the last named textile weft threads.

2. An elastic fabric presenting longitudinally on both faces a sequence of plain sections and of transversely ribbed sections spaced apart at regular intervals in order that the air may pass between them so as to ensure ventilation, such ribbed sections being composed of a series of parallel ribs spaced apart and protruding above and under the fabric with respect to said plain sections, each of such ribs comprising interwoven textile warp threads and eight shots of weft thread, the forenamed rubber warp threads being bound neither with the said textile warp threads nor with the shots of weft so as to leave the rubber warp in each rib its full retractability and extensibility.

3. The method of weaving an improved fabric constituted by a sequence of plain sections and of transversely ribbed sections and made up of rubber warp threads, textile warp threads and textile weft threads in the proportion of one rubber warp thread for four textile warp threads, said sections being spaced apart at regular intervals for permitting the air to freely circulate therethrough, such method consisting in producing said plain section by interweaving said rubber warp threads, said textile warp threads and a multiple of eight shots of weft and producing said ribbed sections by interweaving said textile warp threads with a multiple of eight shots of weft corresponding to the number of ribs in each ribbed section without binding the said rubber warp threads, so as to leave the latter their full retractability and elasticity in each rib, said interweaving being obtained by suitably raising and lowering said textile warp threads.

In testimony whereof I have signed my name to this specification.

ALFRED LAURAIN.
